SMOKE PURIFIER

INVENTOR.
BY *Francis H. Cullen*
W. B. Williamson

UNITED STATES PATENT OFFICE

2,366,700

SMOKE PURIFIER

Francis H. Cullen, Philadelphia, Pa.

Application February 23, 1942, Serial No. 431,939

21 Claims. (Cl. 131—173)

My invention relates to new and useful improvements in a smoke purifier for tobacco smoking appliances, for purifying the smoke entering into the mouth of the smoker.

The purpose of the invention is to provide improved means for absorbing the oils and other objectionable substances from the smoke fumes and in addition to pass the fumes through a liquid bath to further condense, cool, sweeten and purify them so as to prevent tongue burning and biting and give the smoker a pure, cool, sweet smoke.

The general object of the invention is to provide a novel construction of a smoking appliance, which provides a danger signal, to warn the smoker that the condensation and saliva formed in the smoking appliance, due to smoking, must not be exceeded, otherwise, the smoker will draw some of the condensation into his mouth. This danger signal may also be used to warn the smoker that any liquid he may first employ in the smoking appliance, plus the condensation due to smoking, must not be exceeded, otherwise, the smoker will draw some of the combined liquid and condensation into his mouth.

Another object of the invention is to provide a danger signal that may be used to register a portion of the condensation and saliva formed within the smoking appliance, due to smoking, to warn the smoker that this danger point must not be exceeded, otherwise, the smoker will draw into his mouth some of the condensation and saliva. The said danger signal may also be used to register a portion of the liquid that is first employed in the appliance plus the condensation that may form due to smoking.

Another object of the invention is to provide a measuring means so that the smoker may know that he has placed enough liquid, where first employed in the appliance, to form a liquid seal.

Another object of the invention is to provide a removable tubular member within the discharge chamber of a smoking appliance, said tubular member containing a partition, the forward end of the member or end nearest the tobacco bowl forming an inlet or receiving tube and the other end of the member or part beyond the partition, nearest the mouthpiece, forming the outlet or discharge tube.

Another object of the invention is to provide a tubular member with a condensing cylinder, said cylinder being a part of or detachably connected to said tubular member.

A further object of this invention is to provide a tubular member and an attachable condensing

cylinder, either or both of which may be made of either an inexpensive or absorbent material and after they have served their purpose may be discarded and thrown away.

5 A still further object of the invention is to provide a tubular member that is removable and which may be made, for instance, from specially treated paper, such as parchment paper and said member may have an outer jacket of parchment paper and an inner layer of absorbent material or any other suitable filtering substance.

With the above and other objects in view, this invention consists of the details of construction and combination of elements hereinafter set forth 10 and then designated by the claims.

In order that those skilled in the art to which this invention appertains may understand how to make and use the same, I will describe in detail certain means for carrying out the objects 15 of this invention, referring by numerals to the accompanying drawing forming a part hereof, in which:

Fig. 1 is a longitudinal sectional view of a tobacco pipe constituting one form of a smoking 20 appliance embodying the features of my invention.

Fig. 2 is a side elevation of the mouthpiece end of the pipe.

Fig. 3 is a similar view of the bowl end of the 25 pipe.

Fig. 4 is a longitudinal sectional view of another arrangement of the tubular member.

Fig. 5 is a similar view of a modified form of 30 tubular member and portions of the induction and eduction tubes connected therewith and illustrating a slightly different assembly.

Fig. 6 is a sectional view of the condensing cylinder.

Fig. 7 is also a sectional view of the tubular 35 member and condensing cylinder shown in Fig. 1.

In carrying out my invention as herein embodied, 10 represents a pipe bowl comprised of glass or other transparent material, or wood, metal, meerschaum, clay or other appropriate material and said bowl is carried by the hollow shank 11. The pipe bowl has a chamber 12 and a discharge chamber 13, a portion of the latter being provided by the hollow construction of said shank. A section of the wall of the pipe bowl extends into or part way across the discharge chamber in the form of a ledge 14 having a hole 15 through it for the reception of the induction tube to be presently described. A secondary, inner or tobacco bowl 16 is fitted in 40 said chamber 12. The inner or tobacco bowl

can also be made from glass or other suitable transparent material, or wood, metal, merschaum, clay or other appropriate material.

The shank 11 preferably has a reduced end on which is mounted the mouthpiece 17 including a tubular body portion 18, a hollow intermediate portion 19, which may be tapered as shown, both forming a part of the discharge chamber, and a bit 20 having a bore 21 with a socket 22 at the inner end of said bore.

One end of the induction tube 23 is projected through the hole 15 in the ledge 14 and inserted in a hole in the tobacco bowl 16 and the other end extends towards the mouthpiece or away from the pipe bowl and within the discharge chamber. On this induction tube 23 is formed a rib 24 or equivalent formation to provide a stop shoulder 25. This induction tube may vary in length and may have lateral port openings 23' but this will depend upon the length of said induction tube, which can be seen from a comparison of Figs. 1 and 5.

One end of an eduction tube 26 is inserted in the socket 22 in the mouthpiece and the other end extends away from the bit of said mouthpiece or towards the pipe bowl within the discharge chamber and in endwise alignment with the induction tube 23. This eduction tube 26 is also provided with a rib, flange or equivalent formation 27 to furnish a shoulder 28. Said eduction tube 26 may vary in length and may have lateral port openings 26' depending upon the length thereof, the same as the induction tube 23.

On the adjacent or inner ends of both the induction and eduction tubes are placed the ends of the tubular member 29 or an equivalent member such as shown at 29a and 29b. The tubular member 29 is open at both ends so as to communicate with the induction and eduction tubes and has a partition or barrier 30 intermediate its ends.

A condensing cylinder 31, of any kind of material, absorbent or non-absorbent, is of larger diameter than the tubular member 29 but of smaller diameter than the interior of the smoking appliance, and is open at the forward end or that end nearest the pipe bowl and is closed at the opposite or rear end by a wall 32 having a hole 33 therethrough for registration with the tubular member 29 on which the condensing cylinder is mounted and which condensing cylinder defines the condensing chamber 34 from the discharge chamber 13. The normally open end of the cylinder 31 engages the ledge 14 so that the major portion of said normally open end is temporarily closed except for an outlet orifice 35 from the condensing chamber 34 to the discharge chamber 13. Where no liquid is first employed in the device, the cylinder 31 need only be adjacent to the ledge 14.

When the condensing cylinder 31 is properly positioned on the tubular member 29 the end wall 32 should be in the region or general location of the partition 30 so that the lateral port openings 36, in said tubular member, will be outside of the condensing cylinder and form, either by themselves as in Fig. 5 or in conjunction with openings 26' as in Fig. 1, a communication between the discharge chamber 13 and the interior of the tubular member 29 to the rear of the partition 30, and lateral port openings 37 also in said tubular member will be inside of the condensing cylinder and provide, either by themselves, as indicated by 37b, Fig. 5, or in conjunction with openings 23', Fig. 1, a communication between the in-

terior of the tubular member 29, forward of the partition 30, and the condensing chamber 34.

In order to properly position the condensing cylinder 31 on the tubular member 29 and prevent the cylinder from sliding backward, said tubular member may have a flange, rib or other suitable formation 38 to engage the outer surface of the end wall 32 and hold the condensing cylinder in place against the ledge 14.

10 The tubular member 29 is supported by the induction and eduction tubes and in turn said tubular member supports the condensing cylinder in cooperative relation to the ledge 14.

15 The outlet orifice 35 from the condensing chamber is to be sealed by a liquid 39 contained in the discharge chamber 13 and this liquid will contact the inner closed end of the tobacco bowl to keep the latter cool. The amount of liquid to be placed in the discharge chamber can be determined, especially where the smoking appliance is of transparent material, by providing an index or indicator 40 comprised of a groove, line, or ring, either plain or colored, and situated at a suitable location on some part of the smoking appliance, as the shank 11, to the rear of the outlet orifice 35, to denote the liquid level when a sufficient quantity of liquid has been placed in the discharge chamber to insure the sealing of said outlet orifice 35.

20 30 In addition, another similar index, indicator or danger signal 41 can be provided on a suitable part of the smoking appliance, as the shank 11, to the rear of and adjacent the indicator 40, to function as a warning signal to caution the smoker that an accumulation of saliva, condensation and tobacco juices added to the liquid purposely placed in the discharge chamber must not exceed an amount denoted by said danger signal 41 or the smoker will draw some of the mixture 25 35 into his mouth. If and when the accumulations reach the danger signal or indicator 41, the mixture should be replaced by a proper quantity of fresh liquid. When no liquid is first employed this danger signal will register the accumulated condensation and saliva, which accumulations 40 45 should be emptied out of the appliance.

40 45 In connection with the above mentioned indicators another one, designated by the numeral 42, can be provided on the mouthpiece 17 also to function as a danger signal to warn the smoker that the liquid level of condensation and saliva accumulations in the smoking appliance must not exceed the amount indicated by the indicator 42, when the pipe is inverted, for testing purposes, or some of such accumulations will be drawn into the mouth during smoking operations. The indicator 42 may be used also to indicate a portion of the liquid first employed and the accumulated condensation and saliva. The indicator 60 65 70 75 42 may be used to measure the liquid that is to seal the outlet orifice.

In Fig. 4 I have shown the tubular member 29a as including two concentric tubes 43 and 44, the inner one, 44, being of absorbent material. Like the first described form, this tubular member has the partition 30a in the bore thereof with the lateral port openings 36a and 41a through the walls thereof on opposite sides of said partition, and also the rib, flange or equivalent formation 38a.

The showing in Fig. 5 illustrates that the tubular member 29b may have the partition 30b formed integral with the side walls of said member and like the other constructions this tubular member 29b has the lateral port openings 36b

and 37b and the external rib, flange or equivalent formation 38b.

From the foregoing it will be obvious that the smoking appliance can be placed in various positions without the likelihood of the liquid reaching the interiors of the induction and eduction tubes through their respective port openings and entering the tobacco chamber or the smoker's mouth. This is due to the positions of the lateral port openings in the tubular member 29 relative to the surrounding walls and to the fact that said lateral port openings are at right angles to the general direction of flow of the liquid when the smoking appliance is upended in either direction.

During the smoking of the pipe, the path of travel of the draft is from the tobacco bowl then through the induction tube 23, the forward or induction end of the tubular member 29, the lateral port openings 37, the condensing chamber 34, outlet orifice 35, the liquid seal 39 in the discharge chamber, said discharge chamber, the lateral port openings 36, the rear or eduction end of the tubular member, the eduction tube 26, and the opening 21 in the bit 20 to the smoker's mouth. During the travel of the smoke it will be cooled, foreign matter precipitated in the condensing chamber or caught by the sealing liquid and the smoke moistened and sweetened by said sealing liquid prior to reaching the smoker's mouth. Thus it will be apparent that practically all impurities that might be carried by the smoke are eliminated and a cool, highly enjoyable smoke is provided.

To remove the tubular member 29 and the condensing cylinder 31, it is only necessary to disengage the mouthpiece 17 of the smoking appliance from the shank 11 which will pull one end of said tubular member 29 from either the induction tube 23 or the eduction tube 26 or both. Due to the loose fitting connections between all of these parts; or one joint may be tight and the other loose to preselect the point at which they will be disconnected. Then by giving a flicking motion to the mouthpiece, if the tubular member is disengaged from the induction tube, or a similar motion to the pipe bowl portion, if the tubular member is disengaged from the eduction tube, the unit or possibly the condensing cylinder and then the tubular member will be completely disengaged for discarding purposes.

Upon removal of the tubular member 29 and the condensing cylinder 31, the elements of the smoking appliance may be temporarily reassembled and a pipe cleaner projected through the bores of the several smoking appliance elements for cleaning purposes.

Of course I do not wish to be limited to the exact details of construction herein shown and described, as these may be varied within the scope of the appended claims without departing from the spirit of my invention.

Having described my invention what I claim as new and useful, is:

1. A smoking appliance comprising a bowl with a shank and a mouthpiece and containing a discharge chamber, induction and eduction tubes, a tubular member removably mounted on the induction and eduction tubes, said tubular member having lateral port openings at longitudinally spaced locations and communicating with corresponding openings in said induction and eduction tubes and separated by a partition within said tubular member, and a condensing cylinder supported by the tubular member and defining a condensing chamber, said condensing and dis-

charge chambers being in communication through an outlet orifice.

2. A smoking appliance consisting of a housing including a tobacco holding chamber and a mouthpiece and containing a condensing chamber and a discharge chamber between the tobacco holding chamber and the mouthpiece and further having an outlet orifice from the condensing chamber to the discharge chamber, a liquid to seal said outlet orifice, induction and eduction tubes, and a tubular member mounted on the induction and eduction tubes within the housing between the tobacco holding chamber and the mouthpiece and projected through the condensing chamber, said tubular member having a barrier intermediate its ends and between said induction and eduction tubes whereby an inlet end and an outlet end are formed, said inlet end communicating with the condensing chamber through lateral port openings and said outlet end communicating with the discharge chamber through other lateral port openings.

3. In a smoking appliance containing induction and eduction tubes, a discardable unit comprising a condensing cylinder, a tubular member mounted on the induction and eduction tubes and projected longitudinally through one end of said cylinder, said tubular member having two sets of lateral port openings communicating with corresponding openings in the induction and eduction tubes, one set within the cylinder and the other set outside of said cylinder, and a barrier in the tubular member between the sets of port openings.

4. In a smoking appliance containing induction and eduction tubes, a discardable unit comprising a tubular member with lateral port openings in longitudinally spaced locations and communicating with corresponding openings in the induction and eduction tubes, and a barrier in said tubular member between the port openings, means for mounting the tubular member on the induction and eduction tubes, and a condensing cylinder having an open end and an apertured closed end removably mounted on the tubular member and disposed to enclose one of the sets of lateral port openings.

5. The structure in claim 4, in combination with stop means on the tubular member to engage the closed end of the condensing cylinder.

6. A smoking appliance comprising a bowl with a shank and a mouthpiece and containing a discharge chamber to hold liquid, and a condensing chamber, an induction tube mounted in the bowl and projecting into the condensing chamber, an eduction tube mounted in the mouthpiece and projecting into the discharge chamber in endwise alignment with the induction tube, a tubular member removably mounted on the adjacent ends of said induction and eduction tubes, said tubular member having lateral port openings at longitudinally spaced locations and communicating with corresponding openings in the induction and eduction tubes, a barrier in said tubular member between the port openings to form inlet and outlet ends, and a condensing cylinder detachably mounted on said tubular member and enclosing the port openings in the inlet end and defining said condensing chamber and having an outlet orifice providing a communication between said condensing and discharge chambers.

7. The smoking appliance in claim 6 in combination with means for indicating the proper quantity of liquid that should be held in the discharge chamber.

8. The smoking appliance in claim 6 in combination with two adjacent indicators to denote the proper and danger levels of a liquid contained in the discharge chamber.
9. The smoking appliance in claim 6 in combination with a liquid level indicator on the mouthpiece of said smoking appliance to indicate a portion of the liquid held in the discharge chamber.
10. A smoking appliance comprising a bowl with a shank of transparent material, a mouthpiece of transparent material, said mouthpiece and shank being detachably connected with each other and constituting a housing forming a discharge chamber adapted to hold liquid that may be placed in the appliance and condensation and saliva formed from smoking the appliance, a condensing cylinder in the housing to provide a condensing chamber in communication with the discharge chamber through an outlet orifice, means to form a communication between the bowl and the condensing chamber, means to provide a communication between the discharge chamber and mouthpiece, and means on the housing to indicate a liquid level line in the discharge chamber.
11. The smoking appliance of claim 10 wherein the means for indicating the liquid level is on that portion of the housing adjacent the bowl.
12. The smoking appliance of claim 10 wherein the indicating means for indicating the liquid level consists of two indexes in adjacent spaced relation.
13. A smoking appliance comprising a bowl with a shank, a mouthpiece of transparent material, said mouthpiece and shank being detachably connected with each other and constituting a housing forming a discharge chamber adapted to hold liquid that may be placed in the appliance and condensation and saliva formed from smoking the appliance, a condensing cylinder in the housing to provide a condensing chamber in communication with the discharge chamber through an outlet orifice, means to form a communication between the bowl and the condensing chamber, means to provide a communication between the discharge chamber and the mouthpiece, and indicating means on the mouthpiece to indicate a liquid level of a portion of the combined liquid and condensation and saliva in the discharge chamber.
14. The smoking appliance of claim 13 having an indicating means on the housing to indicate a liquid level of a portion of the condensation and saliva formed in the discharge chamber due to smoking.
15. The smoking appliance of claim 13 having an indicating means adjacent the pipe bowl to measure the liquid placed in the appliance that is necessary to seal the outlet orifice.
16. In a smoking appliance containing condensing and discharge chambers, induction and eduction tubes, a discardable unit comprising a condensing cylinder with tubular means forming a communication between the induction tube and the condensing chamber, and tubular means forming a communication between the discharge chamber and the eduction tube.
17. In a smoking appliance containing condensing and discharge chambers, induction and eduction tubes, and a discardable unit comprising a condensing cylinder with tubular means forming a communication between the discharge chamber and the eduction tube.
18. In a smoking appliance containing condensing and discharge chambers, induction and eduction tubes, and a discardable unit comprising a condensing cylinder with tubular means therein, said means forming a communication between the condensing chamber and the induction tube.
19. A smoking appliance consisting of a housing including a tobacco holding chamber and a mouthpiece and containing a condensing chamber and a discharge chamber between the tobacco holding chamber and the mouthpiece and further having an outlet orifice from the condensing chamber to the discharge chamber, a liquid to seal said outlet orifice, induction and eduction tubes, the induction tube projecting into the condensing chamber, means to close the end of the induction tube contained within the condensing chamber except for a lateral port outlet, the eduction tube forming a communication between the discharge chamber and said mouthpiece, and means on the housing to indicate a liquid level line in the discharge chamber.
20. A smoking appliance including a housing, said housing comprising separable parts, a tobacco-holding chamber, one of said parts constituting a mouthpiece, an induction tube and an eduction tube, a tubular member removably mounted on the induction and eduction tubes and positioned within the housing between the tobacco-holding chamber and the mouthpiece portion of the housing, said housing providing a discharge chamber, a condensing cylinder mounted on the tubular member and providing a condensing chamber, said condensing chamber and discharge chamber being in communication through an outer orifice provided at one end of the condensing chamber, said tubular member having lateral port openings at longitudinally spaced locations and communicating with corresponding openings in the induction and eduction tubes and with the condensing chamber and the discharge chamber, and a barrier in the tubular member between the lateral port openings.
21. In a smoking appliance containing induction and eduction tubes, a discardable tubular member with lateral port openings in longitudinally spaced locations and communicating with corresponding openings in the induction and eduction tubes, and a barrier in said tubular member between the port openings, said tubular member being removably mounted on said induction and eduction tubes.

FRANCIS H. CULLEN.
